Primary Examiner — Amber R Stiles*Assistant Examiner* — Christen Pilar Brown-Lorrig(74) *Attorney, Agent, or Firm* — Nelson Mullins Riley & Scarborough LLP(57) **CLAIM**

The ornamental design for a tab for a compression garment, as shown and described.

DESCRIPTION

FIG. 1 is a left side perspective view of a tab for compression garment in use;

FIG. 2 is another left side perspective view of a tab for compression garment in use;

FIG. 3 is a right side perspective view of a tab for compression garment;

FIG. 4 is a right side elevation view thereof;

FIG. 5 is a left side elevation view thereof;

FIG. 6 is a front elevation view thereof;

FIG. 7 is a rear elevation view thereof;

FIG. 8 is a top plan view thereof; and,

FIG. 9 is a bottom plan view thereof.

The broken lines showing a stocking in FIG. 1 and a sleeve in FIG. 2 depict environment and form no part of the claim.
